UNITED STATES PATENT OFFICE.

WILLIAM S. HARLEY, OF MILWAUKEE, WISCONSIN, ASSIGNOR TO HARLEY-DAVIDSON MOTOR CO., OF MILWAUKEE, WISCONSIN.

ENGINE CONSTRUCTION.

1,360,110.

Specification of Letters Patent. Patented Nov. 23, 1920.

Application filed September 19, 1917. Serial No. 192,117.

To all whom it may concern:

Be it known that I, WILLIAM S. HARLEY, a citizen of the United States, and resident of Milwaukee, in the county of Milwaukee, 5 and State of Wisconsin, have invented certain new and useful Improvements in Engine Construction: and I do hereby declare that the following is a full, clear, and exact description thereof.

- 10 My present invention relates to improvements in internal combustion engine structure, particularly that type of engine adapted for use on motorcycles and similar light vehicles.
- 15 The principal object of the invention is to produce a simply constructed and a light internal combustion engine for motorcycles, which will be extremely compact. With this object in view a radical departure in the appearance of such engines has been made, the 20 opposed cylinder type being modified and equipped with improvements to allow its being used on motorcycle frames.

In attaining a compact and light engine 25 the usual crank case has been modified to allow the selective gear transmission mechanism to be mounted therein.

A further object of the invention is to provide an improved arrangement for actuating the valves of the opposed cylinders of 30 the motor.

A still further object is to provide an improved closure cap for the filling opening of the crank case.

35 With these and other objects in view, the invention resides in the novel features of construction, combination and arrangement of parts, which will be hereinafter more particularly claimed and shown in the 40 drawing wherein:

Figure 1 represents a substantially vertical transverse sectional view through a motorcycle power plant constructed in accordance with my invention.

45 Fig. 2 is a vertical section taken substantially on the line 2—2 of Fig. 1.

Fig. 3 is a similar view on the plane of the line 3—3 of Fig. 1, and

50 Fig. 4 is a detail elevational view showing the means for holding the shiftable gear of the selective speed transmission mechanism in any one of its four positions.

Inasmuch as several of the features illustrated in the drawings of the present invention form the subject matter of co-pending companion applications Serial Nos. 192,116,

and 192,658, and Patent No. 1,254,799, only so much of the remaining structure, which the applicant considers to be novel with him, will be described in detail and claimed in the 60 appended claim.

Broadly the power plant consists of an elongated crank case 1 having a centrally arranged circular opening 2 in each opposite side wall substantially intermediate the 65 ends, these openings receiving the inner ends of horizontally positioned opposed engine cylinders 3 and 4 in which pistons (not shown) are designed to reciprocate, and means for translating the reciprocative motion of said pistons to the rear wheel of a motorcycle. In the lower end of the crank case 1 is disposed a crank shaft 5 to which the pistons are connected, the straight portions of said crank shaft being journally 75 mounted in the side walls 6 and 7 of said case 1. Both ends of said crank shaft extend outwardly of the crank case, one being provided with a fly wheel 8 and the other with a spur gear 9.

The gear 9 is disposed in engagement with the outer side of the wall 6, the latter, together with a crank case cover 10, forming a gear case to house the train of gears of which the gear 9 forms a unit, and the 85 clutch 11. One of the units of said train of gears operates an oiler 12, which is constructed in accordance with Letters Patent No. 1,254,799 granted to me on January 29, 1918.

The clutch 11 forms a part of a selective speed transmission mechanism and is mounted upon one end of a drive shaft 13, which is journally mounted in bearings in the walls 6 and 7 of the crank case adjacent 95 the top thereof, said shaft being extended parallel to the crank shaft and therefore transversely of the crank case. A sprocket wheel 14 connected with the end of the drive shaft 13 on the opposite side of the crank case from the clutch 11 is adapted to have a sprocket chain trained thereover and around the sprocket on the rear wheel of a motorcycle upon which the power plate is mounted.

As in all transmission mechanism, the clutch 11 is designed to disengage a drive shaft 13 from the crank shaft 5 to allow a shiftable gear 15 to be meshed with any one of three other gears so as to change the 110 speed ratio between the crank shaft and the motorcycle drive wheel, or moved into a

neutral position. The clutch may be operated in any preferred manner, said mode of operation forming no part of the present invention.

5 In the present case the shiftable gear 15 which is splined upon the shaft 13 is preferably moved by means of a shifting arm 16 connected with one end of a rock shaft 17, the latter extending through one wall of the 10 gear case. The shaft 17 is rocked by a suitable lever (not shown) mounted in a suitable position on the motorcycle frame, and a connection 18 between the lever and an arm 19, which is keyed on said rock shaft. Also 15 fixed on the rock shaft and forming a part of the arm 19 is a latch plate 20 provided with four ratchet notches into any one of which a spring plunger 21 is movable; said plunger being mounted in a suitable housing 22 carried by an ear 23 which is cast upon the outside of the crank case 1. As the parts are shown in Figs. 1 and 4, the shiftable gear 15 is in a neutral position and the plunger 21 in one of the notches of the plate 20 where it will remain until the arm 19 is forcibly moved.

Each of the cylinders 3 and 4 is provided with an intake and exhaust valve which include stems 24 and 25 respectively. For 30 operating these valves and opening and closing the same at the proper time a cam shaft 26 is mounted in the gear casing of which the cover 10 forms a part, said cam shaft having a pair of cams 27 and 27' carried 35 thereby. The cam shaft is caused to continuously rotate with the crank shaft 5 by being connected with the gear 9 by means of a similar gear 28. Also disposed within the above-mentioned gear casing are two 40 pairs of levers 29 and 29', one pair being disposed on each side of the cam shaft and pivoted at one end therebelow, the pivotal connections being provided by pins 30. The free ends of the levers are disposed upwardly 45 as shown in Fig. 2 and engage with the inner ends of push rods 31 which extend through bearings 32 formed in the front and rear walls of the crank casing 1; said push rods serving their usual purpose of actuating the valve stems by engagement with the inner ends thereof. The cams 27 and 27' alternately act upon the levers 29 and 29', they being designed to engage said levers intermediate their ends. Thus the provision 50 of the levers 29 and 29' readily allow the cams 27 and 27' to act upon the valve stems 24 and 25 without causing such cams to be of excessive size or length. Specifically the addition of the levers allows the valves to 55 be actuated by a very compact arrangement which is essential in engines of the type illustrated.

Access to the crank case 1 for the purpose of adding oil or the like thereto is provided 60 through a pair of inlet openings 35 in the

top of said case. These openings are normally closed by a pair of flanged plugs 36, the same being connected together by a spring plate 37. The intermediate portion of the plate is apertured to receive a post 38 70 which is mounted on the crank case by being threaded thereinto. A nut 39 on the outer end of the post allows the tension of the spring plate to be readily regulated and varied whereby to hold the plugs 36 tightly 75 in place.

From the foregoing description taken in connection with the accompanying drawings, it will be seen that a very simply constructed motorcycle engine has been produced and one which will be not only compact but also light because of the disposition and economy of parts. The use of opposed engine cylinders together with a crank case 80 in which is disposed a selective speed transmission mechanism is believed to be an important feature of the invention. 85

I claim:—

In a machine of the class described, comprising in combination, a vertically elongated crank case having a pair of aligned cylinder openings in its opposite walls at its lower end, a horizontally positioned cylinder carried in each of said openings, a horizontal crank shaft disposed in the lower end of the 90 crank case transversely thereof and having its opposite ends journaled in the opposite side walls, a drive gear on one end of the crank shaft externally of the crank case, and adjacent one side thereof, a peripheral 95 flange extending from each of the last mentioned sides of the crank case and disposed laterally of the face thereof, a drive shaft disposed in the upper end of the crank case 100 transversely thereof and having its opposite ends journaled in the opposite side walls, said ends being extended externally of the 105 crank case, a counter shaft in the upper portion of the crank case between the crank shaft and the drive shaft and parallel thereto, the ends of said counter shaft being journaled in the opposite side walls of the case, a clutch on the drive shaft externally of the crank case and on the side thereof 110 adjacent said drive gear, a gear train connecting the drive gear and clutch, a crank case cover disposed over the last-mentioned elements and having an oil tight engagement with the outer edge of said peripheral flange to form a gear case, selective speed means 115 on said drive and counter shafts, and a driven member on the end of the drive shaft opposite the clutch and externally of the 120 crank case.

In testimony that I claim the foregoing I have hereunto set my hand at Milwaukee, in the county of Milwaukee and State of Wisconsin.

WILLIAM S. U. STILES
